UNITED STATES PATENT OFFICE.

HERBERT E. SMITH, OF MANCHESTER, NEW HAMPSHIRE.

WINDING-MACHINE.

1,104,840.

Specification of Letters Patent.

Patented July 28, 1914.

Application filed September 8, 1913. Serial No. 788,541.

To all whom it may concern:

Be it known that I, HERBERT E. SMITH, a citizen of the United States, residing at Manchester, county of Hillsboro, State 5 of New Hampshire, have invented an Improvement in Winding-Machines, of which the following description, in connection with the accompanying drawing, is a specification, like characters on the drawing representing like parts.

This invention relates to winding machines for winding cloth into bolts and to similar machines and has for an object to provide a safety device which will prevent the accidental rotation of the pivoted stiffening blade and in the preferred form the starting of the machine of this class when the heads and blade are not in proper adjusted position whereby the free end of the 20 blade will be supported during rotation.

Accidental starting of a machine of this class is particularly dangerous because when the machine is stopped and the bolt of cloth removed the stiffening blade is left free to swing about one end as a pivot. If the operator accidentally moves the starting lever the blade swings as it rotates and causes serious damage to the machine and often serious injury to the operator. Another 25 cause of accident is the careless placing of the cloth board in the machine in such a manner that the free ends of the board and blade are not properly clamped. In accordance with the preferred form of my present 30 invention I provide a simple and reliable device which prevents the shifting of the operating lever to start the machine when the parts are in any other position than that in which the ends of the cloth board and stiffening blade are properly engaged and secured.

The novel features of the invention will be fully disclosed in the following specification and accompanying drawings and particularly pointed out in the claims.

Referring to the drawings in which I have illustrated one embodiment of my invention, Figure 1 is a back view of a winding machine showing my improved safety device applied thereto, Fig. 2 is a front view of the sliding head and operating device therefor, Fig. 3 is an end view, and Fig. 4 is a detail view of the heads and blade with a cloth board in position.

55 Referring to the drawings in detail, 1 indicates a supporting frame, 2 and 3 gear

casings forming parts of said frame and 4 indicates a drive shaft. Upon the drive shaft are mounted fast and loose pulleys 5 and 6 which are driven by a belt 7. A belt shifter 8 pivotally mounted on the bracket 9 secured to the frame is provided for shifting the belt 7. A shaft 10, is rotatably mounted in the gear casing 2, and is connected to the drive shaft by suitable gearing. Pivotally mounted upon the inner end of this shaft is a head 11, to which is secured a stiffening blade 12. This head is provided with a slot 13 adjacent the blade to receive a cloth board 14. Slidably mounted in the gear case 3, is a shaft 15, to which is rigidly secured a head 16, and this head is slotted to receive the end of the blade 12 and the cloth board 14 is shown at 17. The lip 18 of this head is somewhat shorter than the lip 19. This shaft 15 is connected to the drive shaft by suitable gearing mounted in the gear case 3 and is mounted to permit a sliding movement for a distance slightly greater than the length of the lip 18, but less than the length of the lip 19. By this means when the shaft 15 with its head 16 is withdrawn the blade will rest against the lip 19 but may swing past the lip 18 to permit the removal of the board 14 and the cloth wound thereon. Connected to the shaft 15 to move longitudinally therewith but permitting free rotation of the shaft is a frame 20 which is V shaped and provided with the arms 21 and 22. A rod 23 is connected to the arm 21 and is slidably mounted in brackets 24 and 25 secured to the gear case 3 and on the end of this rod is a knob 26 positioned to be within convenient reach of the operator. A spring 27 positioned between a collar 28 secured to the rod and the bracket 25 urges the rod inwardly and through the connections previously described tends to move the head 16 toward the head 11. A latch 29 is positioned to engage a slot 30 in the rod 23 and hold it in its outer position when the head 16 is withdrawn from the end of the blade 12. A spring 31 urges the latch toward the rod and insures its engagement in the slot 30 when the head is moved back to remove a bolt of cloth.

The mechanism so far described except for the shape of the frame 20 is of common and well known construction.

In accordance with my present invention I provide a safety device whereby it will be

impossible to operate the belt shifter to move the belt from the loose to the fast pulley when the head 16 is in its withdrawn position, or when this head has been moved forward and has failed to properly engage the blade, thus avoiding accidents resulting from careless operation.

In the mechanism illustrated a rack 32 is connected to the belt shifter as by a link 33 and is provided with ratchet teeth 34. A pawl 35 is pivoted to the gear case 3 and is urged toward the ratchet teeth 34 by a spring 36. The construction of the pawl and rack is preferably such that the shifting of the belt from the fast to the loose pulley is never prevented. A rod 37 is slidably mounted in brackets secured to the gear case 3 and is connected to the arm 22 of the frame 20 so that it will move longitudinally with the shaft 15. Upon this rod 37 is secured a double conical cam 38 adapted as it moves forward to normal position to engage a projection 39 of the pawl 35 thereby swinging the pawl about its pivot to release the rack 32. If however the cam moves beyond the normal position as it will if the stiffening blade is not in position the pawl will be released to engage the rack and prevent starting of the machine. By this mechanism when the head 16 is in position to properly engage the blade 12 the pawl 35 is held out of engagement with the ratchet teeth 34 and the belt may be shifted to the fast pulley. If however the head 16 is withdrawn the cam 38 will be at the left of the projection 39 and the pawl 35 will engage the ratchet teeth 34 preventing the shifting of the belt to the fast pulley. If the latch 29 has been raised to release the rod 23 and thereby the head 16 and the head has moved forward under the influence of the spring 27 but has not properly engaged the blade and the board mounted thereon the operation of the belt shifter will still be prevented. For example, if the cloth board and the blade are not properly positioned as the head 16 moves forward the end of the lip 18 may engage the end of the board, or if the blade is swung forward beyond the lip 18 the head will move too far forward. In either event the cam 38 will be at one side of the projection 39 and will not hold the detent 35 in released position. When the head 16 is in proper position holding the board and blade, the cam 38 will engage the projection 39 to hold the pawl away from the rack and the belt shifter will be free to be operated.

It will be clear to one skilled in the art that various modifications may be made without departing from the spirit of the invention as defined in the claims.

The essential feature of the invention is to provide a device which will prevent accidental rotation of the blade while it is free to swing about its pivotal support.

Having fully described my invention what I claim as new and desire to secure by Letters Patent is;—

1. A machine of the class described comprising aligned rotatable elements, a stiffening blade pivotally connected to one of said rotatable elements and arranged to be clamped by the other rotatable element, a power controlling element movable to cause rotation of said blade and means to prevent movement of the controlling element to cause rotation of the blade except when the blade is properly clamped. 70

2. A machine of the class described comprising a supporting frame, a pair of aligned shafts rotatably mounted therein, a stiffening blade pivotally connected to one of said shafts, a head secured to the other shaft and shaped to receive the free end of said stiffening blade, means for moving one of said shafts axially to release the free end of said stiffening blade, and means controlled by the axially movable head for preventing the application of power to rotate said blade except when said blade is properly engaged by said head. 80

3. A machine of the class described comprising a sliding head, a controlling member connected with said sliding head to be moved thereby, a power controlling element for controlling the power supplied to said machine, and means to prevent the operation of said power controlling element to start the machine except when said controlling element is in a predetermined position, 95 whereby the starting of said machine is prevented except when the sliding head is in proper adjusted position. 100

4. A winding machine comprising a sliding head, a cam connected with said sliding head to be moved thereby, means for controlling the power supplied to said machine, a toothed element connected to said means and a pawl controlled by said cam and arranged to engage said toothed element whereby starting of the machine is prevented when the sliding head is in certain positions. 110

5. A winding machine of the class described comprising a supporting frame, a pivoted head and a sliding head rotatably mounted therein, a cam connected with said sliding head to be controlled thereby, a power controlling element for controlling the power supplied to said machine, a toothed element movable on said support and connected to be moved by said power controlling element, a pawl pivotally mounted on said supporting frame and positioned to engage said toothed element to hold said power controlling element against movement in a direction to start the machine, said cam being arranged to engage said pawl to release said movable element when said sliding head is in a certain position whereby 125 130

accidental starting of the machine when the sliding head is not in proper position is prevented.

6. A cloth winding machine comprising
5 a supporting frame a drive shaft rotatably mounted in said supporting frame, alined shafts rotatably mounted in said supporting frame and geared to said drive shaft to be driven in unison, a pivoted head mounted
10 on one of said alined shafts, a stiffening blade secured to said pivoted head, a sliding head secured to the other alined shaft and shaped to engage said stiffening blade, a power controlling member adapted to con-
15 trol the power supplied to said drive shaft, a rack slidably connected to said frame and connected to said power controlling member, a pawl positioned to engage said rack to prevent movement of said rack and said

power controlling member in one direction, 20 a cam connected to said slidable head to be moved thereby and positioned to engage said pawl whereby when the sliding head is in position to properly engage said stiffening blade the pawl will be held away from said 25 rack to permit free movement of said power controlling member, and whereby when said sliding head is in other positions said power controlling member will be held against movement to set the machine in operation. 30

In testimony whereof, I have signed my name to this specification, in the presence of two subscribing witnesses.

HERBERT E. SMITH.
